L. R. ROBERTS,
TYPE BAR KEY LEVER MECHANISM.
APPLICATION FILED AUG. 7, 1917.

1,428,117.

Patented Sept. 5, 1922.

Fig. 2.

A technical line drawing of a ribbed structure, possibly a mold or a component of a machine. The structure features a series of vertical ribs of decreasing height from left to right. Numbered callouts point to specific features: 11 points to a small rib near the base; 12 points to a rib on the left side; 13 points to a rib on the right side; 14 points to the top edge; 15 points to a rib near the base on the right; 16 points to a rib on the right side; and 17 points to a rib near the top on the left.

UNITED STATES PATENT OFFICE.

LYMAN R. ROBERTS, OF RUTHERFORD, NEW JERSEY, ASSIGNOR TO L. R. ROBERTS TYPEWRITER COMPANY, OF STAMFORD, CONNECTICUT, A CORPORATION OF DELAWARE.

TYPE-BAR KEY-LEVER MECHANISM.

Application filed August 7, 1917. Serial No. 184,850.

To all whom it may concern:

Be it known that I, LYMAN R. ROBERTS, a citizen of the United States, residing at Rutherford, in the county of Bergen, and 5 State of New Jersey, have invented certain new and useful Improvements in Type-Bar Key-Lever Mechanism, of which the following is a specification.

This invention relates to typewriters.

10 It is an object of the invention to provide a typewriter in which the type bars and their operating mechanisms are so constructed and related that the type bars are readily removable as a unit for repair, substitution or the like, without the necessity for disconnection or manipulation of the parts.

15 It is a further object of the invention to provide a typewriter embodying the features mentioned, and at the same time one that is effective in operation, practicable in arrangement, and economical to manufacture.

20 With these general objects, and others which will be obvious to those skilled in the art, in view, the invention consists in 25 the constructions, arrangements and combinations which will first be described in connection with the accompanying drawing, and then more particularly pointed out.

30 In the drawing—

Figure 1 is a perspective view of a portion of a typewriter constructed in accordance with the invention.

Figure 2 is a side elevation of the same.

35 Figure 3 is a fragmentary diagrammatic front elevation of the same.

Figure 4 is a side elevation of one of the key levers and mount therefor, and

40 Figure 5 is a side elevation of the key lever mount.

Referring to the drawings, a frame is provided comprising spaced side members 1 and 2 having forward posts 3 and rear posts 4. The embodiment shown includes in combination with a pivotally mounted type bar an operating member having a portion for engaging the lower edge of the type bar in such manner as to operate the same with a shifting contact and to leave the type bar 45 free for direct separation and removal from the operating member. This operating member may, for example, be a portion of the key lever itself. There is also included provision for a plurality of type bars moving in converging planes and a plurality

of operating mechanisms having portions moving in parallel planes and portions having an operative relation with the type bars of the character just described. As here illustrated as an exemplification, a plurality 50 of type bars 13 are pivotally mounted as hereinafter described to swing in converging planes. Fixed on the front posts 3 is a transverse plate 5 arcuate in form and provided with slots 6 in the upper edge there- 55 of to accommodate a plurality of key levers. These key levers are of different lengths to give the usual multiple bank for the operating keys. To pivotally mount the key levers in accordance with their positions in the 60 key bank, secured to the plate are a number of bearing brackets 8 provided with sockets 9 for the reception of bearing pins 10 carried by the key levers. From Fig. 5, it will be seen that these brackets 8 are 65 staggered both vertically and horizontally, so that the throw of all the key levers will be substantially the same. Each key lever 7 is provided with a portion for engaging the type bars to actuate the same with a 70 shifting contact. In the present embodiment, this portion is in the form of a laterally projecting pin 11. This pin is designed to make a bearing contact with the 75 lower edge of the corresponding type bar. 80 To receive the pins 11, the type bars are formed with cam like portions 12 which are offset from the planes of the type bars, in accordance with the position of the particular type bar in the bank (see Fig. 3). 85

90 The invention in its entirety includes the provision of a readily removable mount in which the type bars are pivotally mounted, the type bars and their operating members having mutual bearing contact surfaces 95 which are brought into engagement by the positioning of the mount in the frame and which are free to become disengaged when the mount is removed. Although capable of various constructions, as here shown, the 100 removable mount comprises a segmental block 14 having supporting projections 15. As will appear from Fig. 1, the posts 4 constitute supporting uprights rigidly fixed to the frame and having flat top faces. The 105 segment 14 is hung between these supporting uprights, the projections 15 resting on the flat top faces of the uprights.

Means is provided for locating or positioning the segment, this locating means be- 110

ing readily disconnectible to permit removal of the segment. As here shown as an example, the segment is located, and also secured, in place, by screws 16 entering the 5 flat faces of the uprights 4.

The lower and convex face of the segmental block is formed with a plurality of radial slots 17 for the reception of the ends of the type bars 13. The type bars are 10 pivotally mounted in these slots by means of an arcuate wire 18 which is seated in a groove in the face of the segmental block. The block is so located that when it is in position (Fig. 1) the lower edges of the type 15 bars have the operative relation with the operating members already described, and it will be seen that the positioning of the mount brings into engagement the mutual bearing contact surfaces.

20 The type bars are normally held in their lowered position by springs 19 each of which is connected to a heel on the type bar and to a bracket 20 carried by the mount 14. Springs 21 secured to a bracket 22 and to 25 the key levers tend to hold the latter in normal raised position.

When a key is struck, the corresponding key lever is depressed, as shown in the dotted lines of Fig. 2. During this movement the 30 pin 11 by sliding over the cam portion 12 of the type bar causes the latter to be raised to printing position. As this movement proceeds, the point of contact between the type bar and the key lever moves upwardly to 35 toward the line through the centers of movement of the type bar and key lever. During this movement, this point of contact approaches the center of movement of the type bar and at the instant of printing the pin 40 11 occupies an angular recess in the type bar, as appears in Fig. 2.

Should it be desired to remove the type bars for repair, substitution, or the like, it is only necessary to remove segment 14, the 45 type bars being free for direct separation and removal from the operating mechanisms (which, in this instance, are the key levers). In other words, no disconnection or manipulation of any of the parts is necessary. 50 Similarly, when the segmental block 14 is replaced, the positioning thereof brings the

type bars and their operating mechanisms into operative relation and again no manipulation or connecting up of parts is necessary.

With the construction described, different sets of type are readily available. At the same time, the removable segment, carrying the type bars, is so mounted that proper alignment is retained.

I claim:

1. In a typewriter, and in combination a relatively stationary frame having supporting uprights, a readily removable type bar segment in which the type bars are pivotally mounted, hung between the supporting uprights and having supporting projections which cooperate with the supporting uprights, and operating members for the type bars separate therefrom and normally engaging the same from below, whereby the type bars are freely separable from their respective operating members when the segment is removed.

2. In a typewriter, and in combination a relatively stationary frame having supporting uprights, a readily removable type bar segment in which the type bars are pivotally mounted to swing in converging planes, operating mechanisms for the type bars mounted to have portions thereof move in parallel planes, said operating mechanisms normally engaging the type bars from below, whereby the type bars are readily separable from their operating mechanisms upon removal of the segment.

3. In a typewriter, and in combination a relatively stationary frame having supporting uprights, a readily removable type bar segment in which the type bars are pivotally mounted, hung between said supporting uprights and having supporting projections which cooperate with the supporting uprights, readily disconnectible means for locating the segment in a given position, operating members for the type bars, said type bars and operating members having mutually engaging contact surfaces freely separable upon removal of the segment and brought into operable relation upon locating the segment in position.

LYMAN R. ROBERTS.
